US00D874299S

(12) **United States Design Patent** (10) Patent No.: **US D874,299 S**
(45) Date of Patent: ** Feb. 4, 2020

(54) **WATCH**

(71) Applicant: **Cartier International AG**, Steinhausen (CH)

(72) Inventor: **Sophie Boulangeot**, Geneva (CH)

(73) Assignee: **Cartier International AG**, Steinhausen (CH)

(**) Term: **15 Years**

(21) Appl. No.: **29/649,309**

(22) Filed: **May 29, 2018**

(30) **Foreign Application Priority Data**

Nov. 30, 2017 (WO) DM/099082

(51) **LOC (12) Cl.** **10-02**

(52) **U.S. Cl.**

USPC **D10/32**

(57) **CLAIM**

The ornamental design for a watch, as shown and described.

DESCRIPTION

FIG. 1 is a front elevational view of a watch showing my new design;

FIG. 2 is a back elevational view thereof;

FIG. 3 is a right side elevational view thereof;

FIG. 4 is a left side elevational view thereof;

FIG. 5 is a bottom plan view thereof;

FIG. 6 is a top plan view thereof;

FIG. 7 is a front, right side perspective view thereof; and,

FIG. 8 is a back, left side perspective view thereof.

The broken lines in the drawing figures depict unclaimed subject matter that forms no part of the claimed design.

1 Claim, 8 Drawing Sheets
